Attnys.

UNITED STATES PATENT OFFICE.

JAMES H. BOYE, OF CHICAGO, ILLINOIS, ASSIGNOR TO THE BOYE NEEDLE COMPANY, OF RAVENSWOOD PARK STATION, CHICAGO, ILLINOIS, A CORPORATION OF ILLINOIS.

HOLDER FOR BALLS AND SPOOLS OF STRAND MATERIAL.

1,130,058.

Specification of Letters Patent.

Patented Mar. 2, 1915.

Application filed August 17, 1914. Serial No. 857,175.

To all whom it may concern:

Be it known that I, JAMES H. BOYE, a citizen of the United States, residing at Chicago, in the county of Cook and State of Illinois, have invented a new and useful Improvement in Holders for Balls and Spools of Strand Materials, of which the following is a specification.

My invention relates to an improvement 10 in the class of devices used for suspending balls or spools of yarn, thread, cord, twine, and the like, in convenient position for paying off the strand to the point of use.

The use for which devices of the kind referred to are more particularly intended is 15 that of suspending the ball or spool flexibly and rotatably from an arm of a person occupied in knitting, crocheting, tatting, and the like work; and it is for that class of work 20 that the present improvement has been devised, though it is adaptable with advantage to other uses, including the use for holding balled cord or twine to be paid out in tying packages.

Devices in the class to which my improvement relates involve, each, as its generally stated construction, so far as the state of the art is known to me, a hoop to surround an arm of the user, a stem loosely hung on the 30 hoop and adapted to pass through the bore of a strand-wound spool, and a stop fixed on, applicable to or adjustable on the lower end of the stem to retain a spool thereon. None of these devices, however, has its stem 35 feature adapted to pierce readily or unobstructively through a solidly wound ball of yarn, thread, or the like, nor, in fact, through any but a bore-containing spool, core or ball wound with such material.

The more important objects of the present improvement are to provide a construction 40 of stop-equipped stem which shall adapt it to readily pierce through a solid ball of the wound material as well as through a bore-containing ball or spool thereof; to cause the piercing end or point of the stem to afford a swivel-joint with a keeper for flexible suspension on the arm-hoop, and enable the connection of the stem with and its discon-

nection from the keeper to be performed 50 with extreme facility; to afford an improved construction of the hoop, whereby its application to and withdrawal from the arm of the user, and the matter of adjusting the aforesaid keeper on and taking it off the 55 hoop, shall be greatly facilitated; and to provide a generally improved and simplified construction of holder in the class referred to.

In the accompanying drawing, Figure 1 60 is a perspective view showing my improvement suspended on an arm of a user of the device; Fig. 2 shows the device in elevation; Fig. 3 is a broken view in elevation showing the keeper connected with the hoop and the 65 swivel-connection with the keeper of the penetrating stem-end; Fig. 4 is a section on line 4, Fig. 3; Fig. 5 is a view like that presented in Fig. 3, illustrating one way of inserting the penetrating stem-point into and 70 separating it from the keeper; Fig. 6 is a view similar to that presented in Fig. 4, but illustrating another way of connecting and disconnecting the stem and keeper, and Fig. 7 is a bottom-end view of the keeper.

The hoop 8 is preferably formed of spring 75 wire with its ends spaced apart and blunted by eyes formed thereon to facilitate applying the hoop to the arm of a user and its removal by pulling it off. Near one end of 80 the hoop it contains a spring loop 9 for the purpose hereinafter explained. The keeper 10, as preferably constructed, is a strip of transversely curved spring metal bent upon 85 itself midway between its ends to form an open sided loop widening toward its upper, closed end and narrowing toward its opposite end, at one side of which the adjacent parts of the legs of the keeper meet, as shown at 10^a in Fig. 7. The edges of these 90 legs are cut away along the opposite narrow side of the keeper to widen the space between them toward the closed end of the loop, this space being relatively narrow toward the lower loop-end, where it merges into a transversely-extending end-slot 10^b 95 terminating in a central insertion opening 10^c somewhat wider than that slot. The

stem 11 is formed near one end with a tapering neck 11^a and a tapering spear-like point 12 extending from its junction with the neck, which should be convexly rounded, as shown at 12^a, to adapt the point to exert in withdrawing it from the keeper the wedging effect hereinafter explained. The stem is provided on its opposite end with a stop 13, shown in its preferred button-like form 10 and which may be permanently fastened in place.

To assemble the parts, the keeper is applied over an end of the hoop and introduced into the loop 9, by springing the latter 15 to open its mouth, through which the keeper may be as readily withdrawn in the same manner to disconnect it from the hoop; and the stem is connected with the keeper by introducing into the latter the point 12. This 20 introduction may be effected, as indicated in Fig. 5, by forcing the point through the opening 10^c, thereby wedging apart the keeper-legs, which spring back into place, when the point has been thus fully inserted, 25 to hug about the neck 11^a and there form a swivel-connection between the keeper and stem which greatly facilitates the use of the device as hereinafter described. The junction at 12^a, which affords a shoulder for seating the stem at its penetrating point in the keeper, enables the stem to be readily separated therefrom by pulling to cause the shoulder to wedge apart the keeper-legs. 30 Another way, indicated in Fig. 6, to effect 35 this connection, is by inserting the point inclinedly through the keeper at the wider part of its loop and then drawing the neck through the lower narrower portion of the space between the keeper-legs and through 40 the slot 10^b into the opening 10^c; and to remove the stem from the keeper this operation may be reversed.

As will be understood, the more usual purpose for separating the stem and keeper is 45 for applying to the former a fresh ball 14 of yarn, or the like, or for removing therefrom an exhausted spool and replacing it with a fresh one. To apply a ball 14 to the stem, the latter is passed point-first centrally 50 through it and thus easily penetrates it to hold it at the stop 13 on the stem. The stem penetrates with the same facility any ball of strand-material not provided with an unobstructed opening through it; and it also, of 55 course, may be introduced through the bore of a wound spool, or the like, as readily as may any of the stems of the prior art, referred to. With a ball 14, or the like, thus 60 on the stem and the latter connected, as described, with the keeper hung on the hoop and the latter encircling the arm of a user, the work of paying off the yarn or other material in knitting, crocheting, or analogous occupation, is performed with the utmost facility, by reason of the flexible suspension of 65

the ball or spool on the arm-encircling hoop and the swivel-connection of the stem and keeper.

I realize that considerable variation is possible in the details of construction thus 70 specifically shown and described, and I do not intend by illustrating a single specific or preferred embodiment of my invention to be limited thereto; my intention being in the following claims to claim protection upon 75 all the novelty there may be in my invention as broadly as the state of the art will permit.

What I claim as new and desire to secure by Letters Patent is—

1. In a holder of the character described, 80 the combination of a spring arm-hoop having spaced ends, a keeper flexibly connected with the hoop, and a pivoted stop-equipped stem having a separable swivel-connection at its point with the keeper.

2. In a holder of the character described, 85 the combination of a spring arm-hoop containing a loop, a keeper flexibly hung in said loop, and a pointed stop-equipped stem having a separable swivel-connection at its point with the keeper.

3. In a holder of the character described, 90 the combination of a spring-wire arm-hoop having spaced blunted ends and containing a loop, a keeper flexibly hung in said loop, 95 and a pointed stop-equipped stem having a separable swivel-connection at its point with the keeper.

4. In a holder of the character described, 100 the combination of a keeper comprising loop-forming spring legs forming an insertion-opening between their lower contiguous ends, and a stem provided on one end with a stop, tapered into a neck toward its opposite end and having a penetrating point extending 105 from the neck forming a wedging seating shoulder at its junction with the latter for supporting the stem in the keeper with the neck in said opening forming a swivel-connection of the stem with the keeper.

5. In a holder of the character described, 110 the combination of a keeper comprising legs forming an open-sided loop and an opening between their lower contiguous ends, the opening in one side of the loop being wider 115 toward the closed upper end than toward the opposite end of the keeper, and a stem provided on one end with a stop, tapered into a neck toward its opposite end and having a penetrating point extending from the 120 neck forming a seating shoulder at its junction with the latter for supporting the stem on the keeper with the neck in the opening between said lower contiguous ends and forming a swivel-connection of the stem 125 with the keeper.

6. A holder of the character described, 130 comprising, in combination, a spring arm-hoop containing a loop, a keeper having spring legs forming an open-sided loop at 130

which it is flexibly suspended in said hoop-loop, and an opening in their contiguous lower ends, and a stem provided on one end with a stop, tapered into a neck toward its

5 opposite end and having a penetrating point extending from the neck forming a seating shoulder at its junction with the latter for

supporting the stem in the keeper with the neck in said opening forming a swivel-connection of the stem with the keeper.

JAMES H. BOYE.
